UNITED STATES PATENT OFFICE.

JOSEPH F. MONTINE, OF CHICAGO, ILLINOIS.

TROLLEY CONSTRUCTION.

Application filed June 27, 1923. Serial No. 648,091.

To all whom it may concern:

Be it known that I, JOSEPH F. MONTINE, a citizen of the United States, residing at Chicago, in the county of Cook and State of Illinois, have invented new and useful Improvements in Trolley Constructions, of which the following is a specification.

My invention relates to aerial tramways for transportation systems for collecting and delivering mails, merchandise, etc., along a route the same comprising an elevated track on which it is mounted for travel and an electric motor driven truck carrying a receptacle containing the mail matter or the like.

The invention has for its primary object the provision of a truck for tramways of the character set forth, wherein a novel and improved means is provided for an uninterrupted flow of current from a source of supply.

The invention also has for an object to provide a novel and improved trolley construction which will at all times be maintained in contact with a source of electric current supply and which will not become disengaged therefrom when the truck is passing around a turn or over one of the supports for the track.

Other important objects and advantages reside in the novel combination and arrangement of parts to be hereinafter described and claimed, and in order that the same may be better understood reference is had to the accompanying drawings forming a part of this specification.

In the drawings,

Figure 1 is a side elevation of a tramway truck constructed in accordance with my invention;

Fig. 2 is an end elevation thereof;

Fig. 3 is a plan view;

Fig. 4 is a sectional view taken on the line 4—4 of Fig. 1;

Fig. 5 is a sectional view taken on the line 5—5 of Fig. 1, and

Fig. 6 is a central longitudinal section through the pulley wheel of the trolley, the support for the pulley wheel being broken away.

Referring specifically to the drawings wherein for the purpose of illustration the preferred embodiment of the invention is disclosed, and in which like reference characters have been used throughout to design-

ate similar parts, numeral 5 has been used to denote a pair of spaced vertical supports, preferably of steel or cast iron and which are connected by longitudinally disposed members 7 and 7^a at their upper and lower ends, respectively. The members 5, 7 and 7^a constitute the frame for the truck, the member 7^a being angular in cross-section and provided with a lateral projection 6, the purpose of which being to provide a means for attachment of the truck to the receptacle or carrier in which the packages will be placed. Securing rivets 8 are employed for connection of the members 5, 7 and 7^a.

It will, of course, be understood that two of these trucks will be employed, one at either end of the receptacle. Either or both of the trucks will be supplied with an electric motor which will be carried by a suitable housing affixed to the horizontal portion of the angle iron 6. Since the details of the receptacle and the motor attachment form no part of the present invention, a further description thereof is unnecessary.

Coming back to the truck, it will be noted that the connected portions of the supporting plate 5 and the upper longitudinal plate 7 are provided with apertures through which the bearings and axles of traction wheels 9 are inserted. The bearing 10 extends beyond one face of the supporting plates 5 and the axle 11 extending therethrough is provided with a pulley 12. Two of these pulleys 12 are provided, one upon each of the axles 11, these pulleys being keyed to the axles so as to drive the traction wheels by means of a belt which will be passed over a pulley of a suitable motor which will be located as found desirable.

The support for the trolley comprises two raised and laterally bent straps 13 which are riveted or otherwise secured to the upper longitudinal plate 7 as indicated at 14. The free end of these straps 13 support a longitudinally disposed plate 15 to which current is supplied from a trolley wheel 16 mounted in a suitable bearing 17 upon the free end of a spring metal arm 18, the other end of which is secured against the rear end of the longitudinal member 15. In order to furnish a connection between the spring arm 18 and the longitudinal member 15, a pair of rivets 19 may be used in spaced relation, the purpose of this construction being to prevent swinging of the arm 18. Current will

be supplied to the trolley wheel 16 from the trolley wire 20 which runs along side the track 21 for supporting the grooved wheels 9.

In order to keep the current introduced to the longitudinal member 15 from being conveyed to the frame of the truck by way of the straps 13, I have provided an insulating block 22 therebetween which latter is capped by a disk 23 having a depending circumferential flange 24, the purpose of which is to prevent injury to the block 22. The members 15 and 13 are connected by means of a bolt 25 which is threaded into the longitudinal member 15. A bushing 26 of insulating material is disposed in the aperture of the strap 13, while an insulating washer 27 is disposed upon the top of the strap 13 to prevent the current passing thereto through the bolt 25. From the foregoing it will be apparent that no current will be conducted to the frame of the truck. A connection is made at the rear portion of the horizontal member 15 whereby the current may be conducted to the motor.

From the foregoing description read in connection with the accompanying drawings, the structural features of my invention will be readily apparent to those skilled in the art without further elaboration.

The operation of the invention may be summarized as follows:

In running along the track 20, the trolley bearing truck will of its weight cause the track wire to sag somewhat, this action being characteristic of aerial tramways or carriers in general. As the truck will thus be slightly lower than normally with relation to the trolley wire 21, contact of the trolley wheel 16 with the latter will be assured as a matter of course. Now, as the truck approaches one of the track supports along the line it will rise to its normal position with relation to the trolley wire due to the rise of the track wire 20 to its normal elevation, as fixed by the support. At this point, a tendency would develop for the trolley wheel 16 to rise out of touch with the trolley wire 21, thus interrupting the passage of current to the motor. The present design of trolley arm 18 is intended to prevent such an occurrence, however, by exercising its inherent tension, automatically when the eventuality arises. Thus, the tension of the arm will be downward, when the truck travels at a higher elevation, the arm still exerting a sufficient pressure upon the trolley wheel 16 to constantly maintain it on the trolley wire 21. After the truck has passed the support and again falls into the sag of the track, it should be noted that the trolley arm 18 is so designed as to yield further in an upward direction in case an excess of sag develops in the track wire, the limit of this yield being reached,

of course, when the free end of the arm 18 meets the longitudinal member 15, the latter thus acting as a bumper to prevent excessive tension of the arm.

As noted, the position of the trolley wheel is practically abreast of the traction wheel of the truck, which reduces variation between the wheels to a minimum when passing over track supports or rounding curves. Also, the provision of a long arm, positioned longitudinally of the truck for yieldably supporting the trolley wheel is a very simple expedient and does not subject the trolley wheel to shock from obstructions with tendency to swerve the same out of alignment, as when a different character of spring, such as a coil spring, would be used. The novel leaf-spring arm immediately yields in the proper direction in a case such as mentioned, and combines strength with ample latitude of action.

While I have described and illustrated the preferred embodiment of my invention, yet it will be distinctly understood that I do not propose to limit myself strictly thereto, since various slight changes and modifications may be made therein without a departure from the spirit of the invention, the scope of which is defined by the following claims.

I claim:

1. A trolley for trucks comprising a support forming an electrical conduit, brackets carried by said truck, insulating blocks between said support and said brackets, protecting caps for said blocks, fastening means for said support and bracket connection, insulating means for said fastening means, and a trolley carried by said support for engagement with a source of electric current.

2. A trolley for trucks comprising a support forming an electrical conduit, brackets carried by said truck, insulating blocks between said support and said brackets, protecting caps for said blocks, fastening means for said support and bracket connection, insulating means for said fastening means, and a trolley carried by said support adjacent one of the wheels of said truck.

3. The combination with the running gear of a truck; of a support, a flexible trolley arm carried by the latter and extending therefrom in a direction parallel to the path of travel, and a wheel carried by the free end of said trolley arm, said support forming a bumper for said trolley arm when the latter yields to excessive pressure by the trolley wire on which the wheel rides.

4. A trolley construction for trucks comprising a support forming an electric conduit, supporting brackets therefor carried by said truck and extending laterally from one side of the truck frame, means for insulating said support from said brackets,

and a trolley yieldably carried by the lower face of said support for engagement with the source of current supply.

5. A trolley construction for trucks comprising a support, supporting brackets therefor extending laterally from one side of said truck for disposing said support in parallelism thereto, a vertically yieldable trolley carried beneath said support, said 10 trolley including a spring metal strap extending in the direction of the length of said support, and a contact element carried by said strap substantially parallel with a traction wheel of said truck.
15. 6. A trolley construction for trucks comprising a support forming an electric conduit, supporting brackets therefor carried by said truck, insulating blocks disposed be-

tween said support and said brackets, protecting caps for said blocks, fastening means 20 for retaining said parts in assembled relation, and a trolley carried by said support for engagement with the source of electric current.

7. The combination with an elevated 25 tram-way truck, of a trolley support disposed in parallelism to said truck and spaced from one side thereof, supporting means therefor, a trolley yieldably carried beneath said support and extending in the direction 30 of the length thereof, and said support serving as an abutment for said trolley to limit the movement thereof.

In testimony whereof I affix my signature.

JOSEPH F. MONTINE.
